UNITED STATES PATENT OFFICE.

RUFUS B. FOWLER, OF WORCESTER, MASSACHUSETTS.

PIANO-ACTION.

1,089,123.

Specification of Letters Patent.

Patented Mar. 3, 1914.

Original application filed July 14, 1906, Serial No. 326,276. Divided and this application filed March 5, 1908. Serial No. 419,264.

To all whom it may concern:

Be it known that I, RUFUS B. FOWLER, a citizen of the United States, residing at Worcester, in the county of Worcester and 5 Commonwealth of Massachusetts, have invented a new and useful Improvement in Piano-Actions, of which the following is a specification, accompanied by drawings, forming a part of the same, representing 10 such portions of an automatic piano as are necessary to illustrate my present invention.

Referring to the accompanying drawings, Figure 1 represents a vertical sectional view of the upper portion of a piano action embodying my improvement, showing a piano key in operative connection with the piano action, and Fig. 2 represents a portion of the mechanism shown in Fig. 1, but showing the piano key disconnected from the 15 piano action. Fig. 3 is a detached and sectional view of the valve chambers and air passages controlled by the valve stem 19.

Similar reference letters and figures refer to similar parts in the different views.

25 My present invention relates to that class of automatic pianos which comprise a pneumatic mechanism for actuating the individual sections of the piano action, and my present invention comprises certain novel 30 features of construction of the piano action in such a piano, as hereinafter described and pointed out in the annexed claims.

Referring to the accompanying drawings 1 denotes the case of the piano, 2 one of the 35 piano strings, 3 a piano action comprising a hammer 4 and wippen 5, pivoted at 6. The construction of this portion of the piano action may, however, be of any known form as it forms no part of my present invention. 40 The free end of the wippen rests upon a lever 7 pivoted at 8 to a bar 9, capable of sliding horizontally in ways 10. The lever 7 is cut away on its under side forming a shoulder 11 and a horizontally extended 45 tongue 12. The lever 7 normally rests upon a capstan 13 carried by the inner end of one of the keys 14 of the keyboard, and the tongue 12 rests upon the upper end of a lifting wire 15 which is provided with a washer 50 16 resting upon the upper surface of a lever 17, attached to a pneumatic motor bellows 18 forming a part of the pneumatic action.

The pneumatic action by which the lifting wire 15 is raised forms no part of my

present invention and may be of any known 55 and suitable form of construction. In the present instance, it consists of a pneumatic mechanism substantially like that shown and described in Letters Patent of the United States No. 888,152 issued to me May 19 60 1908, of which this application is a division, and comprises a motor bellows 18 capable of being connected with vacuum chambers of different tensions, or degrees of vacuum, by means of valve controlled passages 65 having valves operated through the reciprocating motion of a valve stem 19, and normally held in position by means of a spiral spring 20.

Resting upon the upper end of the valve 70 stem 19 is the free end of a lever 21 which is pivoted at 22 to a swinging frame 23, which is pivoted upon brackets 24 attached to the framework of the piano. Attached to the under side of the swinging frame 23 are 75 wedge shaped pieces 25 which are supported upon rolls 26, running upon a horizontal track 27 and pivotally connected by a link 28 with an arm 29 attached to a rocking shaft 30. The lower end of the arm 29 is 80 pivoted to a pull rod 31 having at its outer end a hand knob 32. The rocking shaft 30 carries arms 33 which are pivotally connected by links 34 with the sliding bar 9, to which are pivoted a series of levers 7, 85 upon which are supported the wippons 5 of the piano action.

Resting upon the lever 21 is a short spindle 35 capable of sliding vertically in the framework of the piano, and preferably 90 provided with buttons 36 and 37 at its upper and lower ends. In Fig. 1 the swinging frame 23 is shown in its depressed or lowest position, and, in this position, the upper button 36 of the spindle 35 is sufficiently below the key 14 to allow the key to be pressed in playing the piano without hitting the button, and, in this position, the depression of the key 14 will raise the lever 7 and wippen 5 to actuate the hammer 4 in the usual and 100 well known manner.

If the hand knob 32 be pushed in it will rock the shaft 30, moving its connected parts from the position shown in Fig. 1 to that shown in Fig. 2. The rolls 26 moving beneath the wedge shaped blocks 25 will raise the swinging frame 23 and the pivoted ends of the levers 21 sufficiently to bring the but-

ton 36 on the spindle 35 into contact with the under side of the key 14. The sliding bar 9 will be moved on its ways 10 to bring the capstan 13 beneath the tongue 12, so that the rocking motion of the key 14 will fail to raise the lever 7, thereby disconnecting the keys from the piano action. The tongue 12, however, will still rest upon the upper end of the lifting wire 15, enabling the lever 7 to be raised by the action of the motor bellows 18, and allowing the piano to be played through the medium of the pneumatic mechanism. Any depression of the piano key 14 acting through the short spindle 35 will serve to depress the free end of the lever 21 and push the valve stem 19 downward, thereby shifting the valves of the valve controlled passages and connecting the motor pneumatic 18 with vacuum chambers of different tensions.

When the swinging frame 23 and lever 7 are in the position shown in Fig. 1, the keys of the piano are operatively connected with the piano action and disconnected from the pneumatic controlling mechanism, but when these parts are shifted into the position shown in Fig. 2, the keys will be disconnected from the piano action and brought into operative relation with the pneumatic controlling mechanism, so that, while the piano is being played by the pneumatic mechanism through the lifting wires 15, the force of the blow imparted by the motor bellows 18 may be varied with respect to any one of the piano hammers by depressing the corresponding key of the piano, and thereby depressing the corresponding valve stem 19.

I have not shown in detail the construction of the pneumatic mechanism for actuating the piano action, as the construction and operation of mechanism of this class will be readily understood. In the mechanism herein shown and described, I produce by any suitable means different degrees of tension or air vacuum in the two chambers 38 and 39, shown in sectional view in Fig. 3, said chambers having valve controlled communication through a pipe 40 with the pneumatic mechanism directly concerned in actuating the motor bellows 18. The passage through the pipe 40 communicates with the chamber 41, which is in normal communication with a valve chamber 42, communicating with the vacuum chamber 38.

By the depression of the valve stem 19 the chamber 41 is cut off from the valve chamber 42 and brought into communication with a valve chamber 43, which communicates with the vacuum chamber 39. I do not wish, however, to confine myself to the valve mechanism as shown, as my present invention relates particularly to the mechanism for making and breaking the operative connection between the piano action

and the keys, and between the keys and any suitable mechanism for controlling the tension of the motor bellows 18.

The inner end of the piano key 14 is provided with an adjustable member adapted to bear against the under surface of the pivoted lever 7. In the present instance, this adjustable member consists of a capstan 13, which is preferably bifurcated at its upper end and provided with a small roller 44 which lessens the friction due to the sliding movement of the lever 7, and also to the angular movement of the key 14 in actuating the piano action. The upper surface of the lever 7 is parallel with the plane of movement of the bar 9, so that, as a sliding movement is given to the lever, the free end of the wippen 5 will be maintained in the same horizontal plane. The member 7 may, of course, be employed solely for effecting a connection between the key and the piano action irrespective of the pneumatic controlling mechanism.

I claim,

1. The combination with a piano action and a key, of horizontal ways, a bar capable of sliding in said ways, a lever pivoted to said bar with its upper surface bearing against the wippen of the piano action, a capstan carried by said key and bearing against an under surface of said lever, and means for sliding said bar in its ways to move said lever out of contact with said capstan.

2. The combination with a piano action and a key, of a movable pivoted lever having its upper surface in constant operative relation to the piano action and its under surface capable of being brought into and out of operative relation to said key at will, and means for moving said lever to change its operative relation to said key.

3. The combination with a piano action and a key, of a movable pivoted member in a horizontal position, with the upper surface of said member in one horizontal plane and arranged in operative connection with said piano action and with the under surface of said member in two horizontal planes, connecting means between said key and the lower portion of said under surface, whereby said member is rocked on its pivot by the movement of said key, means for moving said member to bring the higher portion of said lower surface above said connecting means, and means for maintaining said member in said horizontal position.

4. The combination with a piano action and a key, of horizontal ways, a bar slidable in said ways, a lever pivoted to said bar with its upper surface in constant operative relation to the piano action and having an under surface capable of being brought into and out of operative relation to said key.

at will by the sliding movement of said bar in its ways, and means for sliding said bar.

5. The combination with a piano action and a key, of a bar above said key and transverse thereto, a horizontal lever pivoted to said bar, with the upper surface of said lever operatively connected with said piano action and with a portion of the lower surface cut away, a capstan on said 10 key in contact with said lower surface, and means for sliding said bar to bring the cut away portion of said lower surface above said capstan, thereby disconnecting said lever and said key.

15 6. The combination with a piano action and a key, of a horizontal pivoted lever with its upper surface in constant operative connection with said piano action, said lever in one position arranged to be rocked 20 by the movement of said key to actuate said action, means for moving said lever in a horizontal plane out of said position to disconnect it from said key, and a friction roller carried by said key and in contact 25 with the under side of said lever.

7. The combination with a piano action and a key for actuating said piano action, of an interposed member between the piano action and the key consisting of a horizontal 30 slidable pivoted lever having its upper surface adapted to support the piano action, and its lower surface adapted to be acted upon by the key.

8. The combination with a piano action 35 and a key, of a capstan rigidly connected with said key, and an interposed slidable member between the capstan and action, having its upper surface adapted to support the piano action in the same horizontal 40 plane during the sliding movement of said

member and having its under surface adapted to be acted upon by said capstan.

9. The combination with a piano action and a key for actuating the same, of an interposed slidable member having its upper surface adapted to support the piano action in the same horizontal plane during the sliding movement of said slidable member, and having its under surface arranged in two sections in different planes, with one section 50 capable of being brought into operative connection with the key.

10. The combination with a piano action of a slidable bar, a lever pivotally connected with said bar having its upper surface 55 adapted to support the piano action, and having its under surface in two sections in different planes, a key, an adjustable member carried by said key and arranged to contact with one section of said lever when 60 the lever is at one end of its sliding movement, and to clear the other section when the lever is at the other end of its sliding movement.

11. The combination with a piano action 65 and a key, of a capstan rigidly connected with said key, a slidable member interposed between said capstan and said action for operatively connecting and disconnecting said key and action at will, and means for 70 moving said slidable member, comprising a slidable bar to which said member is pivoted, a rocking shaft with radial arms pivotally connected with said bar, and means for rocking said shaft at will.
